Des. 218,720

Patented Sept. 15, 1970

218,720

COMBINED CLIPBOARD AND ADDING MACHINE

Henry Shahan, Placentia, Calif., assignor to Shahan Products Inc., Placentia, Calif., a corporation of California

Filed June 30, 1969, Ser. No. 17,986

Term of patent 14 years

Int. Cl. D19—99

U.S. Cl. D74—2

Fig 1

Fig 2

Fig 3

FIG. 1 is a front elevational view of a combined clipboard and adding machine showing my new design;

FIG. 2 is a side elevation; and

FIG. 3 is a rear elevational view thereof.

I claim:

The ornamental design for a combined clipboard and adding machine, as shown.
